UNITED STATES PATENT OFFICE.

CHARLES R. CLARK, OF CHICAGO, ILLINOIS.

GAS GENERATOR AND BURNER.

SPECIFICATION forming part of Letters Patent No. 552,419, dated December 31, 1895.

Application filed May 24, 1895. Serial No. 550,552. (No model.)

To all whom it may concern:

Be it known that I, CHARLES R. CLARK, of Chicago, in the county of Cook and State of Illinois, have invented a new and Improved 5 Gas Generator and Burner, of which the following is a full, clear, and exact description.

The invention relates to an improvement in that class of gas generators and burners wherein a generating-coil or its equivalent is

10 provided, and made capable of receiving a supply of oil which is subsequently formed into gas by the heat of a burner below; and the main object of the invention is to provide a device which will be especially capable 15 of use in connection with stoves formerly adapted for burning wood and coal, and so that it may be situated in the fire-box of such stoves and made to take the place of the wood or coal fire which formerly heated the stove.

20 This end I attain by certain peculiar features of construction and combination and arrangement of parts, as will be fully described hereinafter, and finally embodied in the claims.

Reference is to be had to the accompanying 25 drawings, forming a part of this specification, in which similar characters of reference indicate corresponding parts in all the figures.

Figure 1 represents a longitudinal section 30 of a burner and generator constructed in accordance with my invention, and showing the manner of arranging it within the stove. Fig. 2 is a plan view of the invention, the deflector-plate thereof having been removed to disclose parts beneath it. Fig. 3 is a vertical 35 cross-section of the burner on the line 3-3 in Fig. 1, and showing the relative arrangement of the fire-box; and Fig. 4 is a detail view, partly in section, and illustrating a tool for use in connection with my invention.

40 The reference-numeral 10 indicates a cast-iron box or casing, which is rectangular in form and which has its upper end open. The box or casing 10 also has its inner side cut away at 11, so that the flame and heat from 45 the burner may more readily and effectively reach the stove and heat the same, as may be seen by reference to Fig. 3. This box 10 is seated within the fire-box 12 of the stove, as shown in the drawings, and the sides of the 50 box are packed with fire brick or clay so as to prevent the entry of air into the box.

The air which is essential to the operation

of the burners is admitted into the box 10 through the openings 13 which are formed in the bottom of the box, the whole being so arranged that these openings will have communication with the atmosphere through the usual draft-openings of the fire-box. It will be understood that the box 10 is so located that the lids of the stove may be placed over it. These lids are not illustrated in the drawings.

Seated within the box 10 is the base-plate 14 of the device, and this base-plate is also rectangular in shape and has projecting downwardly from its edges the flange 15, which has formed therein a series of openings 16, through which the air is admitted from under the base-plate and into the space occupied by the burners. The base-plate 14 has also, at its edges, 70 an upwardly-projecting flange 17.

Rigidly secured to or formed integral with the respective ends of the base-plate 14 and rising vertically therefrom are the standards 18, which are two in number and which have 75 rigidly secured to their upper ends, by means of a bolt 19, the lugs 20 of the frame 21. The frame 21 consists of a bar cast integral and rectangular in form, it being of a size equal to that of the base-plate 14. This bar 80 is angular or L-shaped in cross-section, as may be seen by reference to Figs. 1 and 3 of the drawings, and is provided to carry the generating-coils and mixing-cones, as will be fully described hereinafter. The frame 21 85 is formed with a bend 22 at its middle, and this bend 22 is placed upon half of the frame out of the plane occupied by the remaining half, the purpose of which is to permit the reception of the lower coil 23 of the generating-tube. 90

The generating-tube passes into the box 10 at its inner side and proceeds horizontally throughout the length thereof. It is next curved, as shown at 24, and extended along 95 the opposite side of the box, whereupon it is again formed into the lower coil 23 referred to hereinbefore, and finally extended downwardly to the bottom and central portion of the box, where it is made to communicate with 100 a union casting or T 25. The union or T 25 has two horizontal arms which respectively receive the tubes 26, and these tubes 26 project oppositely and horizontally from the

union and longitudinally with the length of the base-plate 14. The pipes or tubes 26 terminate over the projections 27 formed on the upper side of the plate 14, and are provided with gas-emitting nozzles 28. The nozzles 28 are one for each of the pipes 26 and have their discharge-openings disposed vertically, so that the gas will be directed upwardly therefrom and into the region of the generating-pipe, as will be understood from the drawings.

The frame 21 has formed on its upper side a series of transverse projections 29, upon which the generating-pipe lies, and these 15 projections are provided to assist in the support of the said pipe. The edges of the frame are also provided with upwardly-projecting studs 30, which pass by the coils and serve to hold them against lateral movement. The 20 frame 21 is further provided at each inner side of its ends with curved projections 45, which pass by the inner sides of the coils 24 and 23 and serve to further assist in holding the said coils in place.

25 Formed integral with the under side of the frame 21 and projecting downwardly therefrom are lugs 31, which are extensions of the vertical part of the angle-bars composing the frame 21 and which are adapted to have the 30 arms 32 bear against their under sides. The lugs 31 are four in number and are arranged in two pairs, the members of which are respectively opposite each other, while the arms 32 are one for each of the lugs and are formed 35 respectively two integral with each of the mixing-cones 33. The mixing-cones 33 are formed of cast metal and substantially frusto-conical in form, though the sides are angular, as will be seen by reference to Fig. 2 of the drawings. By means of the arms 32 and lugs 31 these mixing-cones are held rigid on the frame and in the proper position, they being located one with its upper end on the same plane as the coil 23 and the other with its upper end 40 in the same plane and directly below the bend 24 of the generating-tube. The purpose of 45 these devices is to confine the gas escaping from the nozzles 28 and to mix therewith that amount of atmosphere which is well known 50 to be essential to the combustion of the gas. The cones also serve to confine the flame and to direct it properly.

Rising vertically from each end of the frame 21 and extended at a point above the upper 55 edge of the box 10 are the arms 34. These arms are two in number and have their upper ends in the same horizontal plane and formed with open bearings 35, which respectively receive the trunnions 36, formed integral with 60 the deflector-plate 37. The deflector-plate 37 is formed of cast metal and is of a length and width equal to that of the frame 21. The under side of the deflector-plate comprises two downwardly-curved surfaces 38, which come 65 to a juncture at 39 and form thereby a longitudinally-extending rib. The surfaces 38 are curved in the arc of a circle, and the ends of

the plate are provided with arc-shaped projections or plates 40, which are one for each end and which project downwardly therefrom.

The purpose of the plate 37 is to deflect the flame from the cones 33 and to make it possible to direct the same against the oven side of the stove or burners, as may be desired. It 75 will be seen that by swinging this plate on its bearings so that its upper face will be inclined, the flame, upon striking it, will be directed up the inclined under side and in the direction desired by the person using the burner. 80 Formed in the upper side of the deflector-plate 37 are the recesses 41, which are provided for the reception of a manipulating-tube and whereby the plate may be adjusted on its bearings or removed and replaced. 85

When it is desired to shut off the burner, this will, as is well known, be effected by stopping the flow of oil into the generator-tube, but to effect an immediate extinction of the flame I provide the tool illustrated in 90 Fig. 4, which consists of a shank 42 having at one end a cup-shaped device 43 and at the opposite end a drill or punch 44. When now it is desired to immediately extinguish the flame after cutting off the supply of oil, the 95 deflector-plate 37 may be removed and the tool referred to introduced into one of the mixing-cones 33 and the cap 43 made to embrace the emitting portion of the nozzle 28, which is under the cone, so as to cut off the 100 supply of air and extinguish the flame. The drill or punch 44 will be useful to clean the nozzles 28 should they become clogged with 105 deposits from the oil or gas. The object of quickly extinguishing the flame, after the supply of oil has been cut off, is to permit the residue of the oil in the generating-tubes to pass off in the form of unconsumed gas and thus prevent the oil from passing out of the 110 nozzles, which would have the effect of clogging them up with hydrocarbon deposits.

The use and operation of my invention will be well understood, and therefore it will suffice for me to say that in the operation all that will be necessary, after the assemblage of 115 parts, is to turn the oil into the generating-tubes or coils and to ignite that which passes out through the nozzles 28, so that the flame may rise into the vicinity of the generating-coils and heat the same sufficiently to form 120 the gas. As the gas begins to form it escapes through the burners or nozzles 28 and becomes ignited and burns, all of which is the same as in prior devices and needs no further description.

125 It will be understood that the purpose of the lower coil 23 is to allow the gas generated in the tube to be superheated before reaching the burner-nozzles, which operation has a well-known and advantageous effect on the operation of the burner.

Having thus described my invention, I claim as new and desire to secure by Letters Patent—

1. In a gas generator and burner, a supported frame having upwardly extending projections at its ends, a generator coil and burners carried by the frame, and a deflector plate 5 rockably mounted in the projections and having two outwardly and upwardly curved sides with flanges at their ends, substantially as described.
2. In a gas generator and burner, a box, 10 the same having an open top and side, a base plate rested upon the bottom of said box and having at its edges downwardly-projecting flanges, the same having notches therein, standards rising from the ends of the base 15 plate, a frame secured upon the standards and arranged with a bend at its middle whereby it is made to extend in two different planes, the frame having a projection at each end, a deflector plate rockably mounted in said projections, a generating coil, the same having 20 a horizontal upper portion lying upon the higher part of the frame and a parallel lower part resting upon the lower part of the frame, burner orifices, and mixing cones, substantially as described.
